SEPARABLE CLOSURE CAP AND LOCKING MEMBER THEREFOR

Herbert K. Baskin, Brooklyn, N. Y.

Application June 20, 1936, Serial No. 86,259

3 Claims. (Cl. 215—91)

This invention relates to improvements in receptacle closures and has particular reference to a closure cap and locking member therefor adapted for use on bottles, jars and the like.

An object of the invention is to provide an improved closure cap and locking member of simple, practical and economical construction in which the locking member will securely hold the closure cap in its operative position and permit of the easy removal thereof from a receptacle by coaction of the cap and member when the latter is manipulated.

The above and other objects will appear more clearly from the following detailed description when taken in connection with the accompanying drawing which illustrates preferred embodiments of the inventive idea.

In the drawing:

Figure 1 is a fragmentary perspective view of a receptacle such as a bottle or jar showing one form of the invention applied thereto.

Figure 2 is a vertical longitudinal section illustrating, in full lines, the operative position of the cap and locking member, the dotted line position showing the manner of releasing the cap from its position on the receptacle.

Figure 3 is a fragmentary view, partially in elevation and partially in section, showing a slightly modified form of the invention, the dotted lines indicating the releasing position, and

Figure 4 is a perspective view of another form of locking member used in conjunction with the closure cap.

Referring more particularly to the accompanying drawing, the numeral 5 indicates a receptacle of any type to which the closure cap and locking member, generally indicated by the numerals 6 and 7 respectively, may be applied.

As shown in Figures 1 and 2, the closure cap 6, which may be made of any suitable material such as metal or the like, is of circular formation to fit the open end of the receptacle 5, and the top of said cap comprises an annular, flat, marginal portion 8 which is disposed directly above the rim of the receptacle 5 when the closure cap is in position. A washer or gasket 9 forming a seal may be disposed between the receptacle and said portion 8, if desired. The remainder of the top of the cap within the marginal portion 8 is formed into a curved depression 10 for a purpose which will appear in the course of the description. The cap further has a depending flange or rim 11 which encircles and engages the outer periphery of the receptacle 5 when the cap is in position and the free lower

edge of said flange terminates adjacent an annular shoulder 12 formed on the receptacle 5.

The locking member 7, which is utilized to retain the closure cap in its operative position, is preferably formed from an elongated strip of flexible material, preferably having a certain amount of resiliency, such as metal or the like. The intermediate portion of the locking member extends diametrically across the top of the cap 6 when the member is in position and in so doing the ends of said intermediate portion rest upon the marginal portion 8 of the cap, while the remainder of said intermediate portion extends above the depression 10 in the cap in normal spaced relation thereto. At each end of the member 7 the same is bent laterally to form a retaining element 13 which is engageable with the rim 11 of the cap and which terminates in one or more inturned claws 14 adapted to engage beneath the annular shoulder 12 of the receptacle 5 and thereby lock the closure cap thereto. Means are provided for retaining the locking member 7 against lateral shifting with respect to the closure cap such as might occur if the member 7 were accidentally struck sideways. Such means preferably takes the form of a pair of outstruck lugs 15 disposed on the rim 11 and spaced apart sufficiently to receive therebetween the depending retaining elements 13 of the locking member, and thus provide stops against which the edges of said retaining element will contact to prevent the lateral shifting referred to. To remove the cover from the receptacle, it is only necessary to exert a pressure upon the central point of the member 7 to flex the same downwardly and into the depression 10. When such action occurs, the inner edge of the marginal portion 8 of the cover acts as a fulcrum at the two diametrically opposite points which are engaged by the ends of the flat portion of said member 7 and as the flexing of the latter takes place the retaining elements 13 are rocked and swung outwardly to the dotted-line position shown in Figure 2 whereupon the claws 14 will disengage from beneath the shoulder 12 and thus permit the closure cap to be lifted from the receptacle. Said cap may be replaced in its closing position by a reversal of the operation just described.

In the form of the invention shown in Figure 3, the cap 6 and locking element 7 are of substantially the same construction as the embodiment first described and differ therefrom only in the formation of the cap rim and retaining elements of the locking member. The annular rim 16 of the cap 6 is provided at its free lower edge with 55

an annular bead 17 formed by two angularly disposed surfaces of said rim. Likewise, each retaining element 18 of the locking member 7 is bent adjacent its lower edge to form an annular groove 19 adapted to receive the bead 17 when the elements are in operative position. The free extremity of the retaining element 18 contiguous to the groove 19 is bent inwardly to provide the claw 20 which engages beneath the shoulder 12 of the receptacle to lock the cover in position. When the portion of the member 7 above the depression 10 in the cover is flexed into said depression, the action is the same as that previously described and the retaining elements 18 are swung outwardly to disengage the claws 20 from the shoulder 12 as shown in dotted lines in Figure 3. However, due to the bead 17 on the cover the claw 20 of each retaining member 18 will not be swung outwardly sufficient to clear the rim of the cover with the result that said claw will still remain in contact with the bead 17 and the locking member will not become completely detached from the cover, thus avoiding separation and possible loss of either the cover or locking member should it be desired to later use the same in re-closing the receptacle.

Another form of locking member 21 is illustrated in Figure 4 of the drawing in which said member is again made of a flexible material, the member in this instance being bifurcated at its ends as indicated at 22 so as to form two diverging arms 23 each terminating in a laterally extending retaining element 24 similar to the elements 13 and 18, the extremity of each element being inverted to form a claw 25 engaging underneath the shoulder 12 of the receptacle. When the member 21 is in position the divergence of the arms 23 disposes the elements 24 in spaced relation to each other and on opposite sides of the diametric center of the closure cap. By this arrangement, the possibility of any lateral shifting of the locking member relative to the closure cap is reduced and the necessity of employing any retaining means such as lugs 15 may be avoided. The cover 6 of the present modification may be detached from the receptacle in the same manner as described in connection with the other forms of the invention.

What is claimed is:

1. In combination, a closure cap for a receptacle, said cap having a flat annular marginal portion and a central depression in its top, and an elongated flexible locking member extending diametrically across said top with its intermediate

portion disposed over said depression and other portions resting upon said marginal portion of the cap, and retaining elements at the ends of said locking member engageable with the receptacle to hold said cap in closed position, said intermediate portion of the locking member capable of being flexed into said depression and the inner edge of said marginal portion providing a fulcrum for said member when so flexed whereby said retaining elements are released from engagement with said receptacle. 5

2. In combination, a closure cap for a receptacle, said cap having a flat annular marginal portion and a central depression in its top, an elongated flexible locking member extending diametrically across said top with its intermediate portion disposed over said depression and other portions resting upon said marginal portion of the cap, retaining elements at the ends of said locking member engageable with the receptacle 15 to hold said cap in closed position, said intermediate portion of the locking member capable of being flexed into said depression and the inner edge of said marginal portion providing a fulcrum for said member when so flexed whereby said retaining elements are released from engagement 20 with said receptacle, and stop lugs on said cap disposed on opposite sides of and engageable with said locking member to prevent lateral shifting thereof relative to said cap when the member is 25 in locking position.

3. In combination, a closure cap for receptacles, said cap having a top provided with a central depression and further having a depending annular flange provided with a bead extending 35 thereabout, and a flexible locking member for said cap extending thereacross with the intermediate portion of said member disposed above said depression and capable of being flexed into the same when releasing said cap, said locking 40 member having gripping portions at its ends engageable with said flange with the extremities of said gripping portions engaging said receptacle to retain said cover in position thereon and being released from said receptacle when the locking 45 member is flexed into said depression, said gripping portions having grooves to receive said bead when the locking member is in operative position and said bead being engaged by said locking extremities of the gripping portions, when the locking member is flexed, to retain said member 50 on said cover when the latter is removed from the receptacle.
